[57] CLAIM

The ornamental design for a light fixture, as shown and described.

DESCRIPTION

FIG. 1 is a perspective view of a light fixture showing my new design;

FIG. 2 is a front elevational view thereof, with the rear view being a mirror image thereof;

FIG. 3 is a left side elevational view thereof, with the right side view being a mirror image thereof;

FIG. 4 is a top plan view thereof;

FIG. 5 is a bottom plan view thereof;

FIG. 6 is a perspective view of a second embodiment of my new design;

FIG. 7 is a front elevational view thereof, with the rear view being a mirror image thereof;

FIG. 8 is a left side elevational view thereof, with the right side view being a mirror image thereof;

FIG. 9 is a top plan view thereof;

FIG. 10 is a bottom plan view thereof.

The reflector is shown in broken lines in FIGS. 1 and 6 for illustrative purposes only and forms no part of the claimed design.

FIG. 1

FIG. 2

FIG. 3

FIG. 4

FIG. 5

FIG. 6

FIG. 7

FIG. 8

FIG. 9

FIG. 10
